Term of patent 14 years

Int. Cl. D6—13

U.S. Cl. D6—271

FIG. 1 is a top plan view of a place mat and napkin set showing my new design, the details of the place-mat edging shown at the bottom and right of FIG. 1 being continuous on all sides, the napkin shown in the pocket portion being of conventional proportions and plain except for the continuous edging which is as shown on one corner of the napkin; and

FIG. 2 is a bottom edge view of FIG. 1.

I claim:

The ornamental design for a place mat and napkin set, substantially as shown and described.
